UNITED STATES PATENT OFFICE

146,237

DESIGN FOR A PAIR OF EYEGLASSES

Philip Sills, Brooklyn, and Frank P. Patalano,
New York, N. Y.

Application February 16, 1946, Serial No. 126,621

Term of patent 3½ years

(Cl. D57—1)

To all whom it may concern:

Be it known that we, Philip Sills, a citizen of the United States, residing in Brooklyn, in the county of Kings and State of New York, and Frank P. Patalano, a citizen of the United States, and residing at New York, in the county of New York and State of New York, have invented a new, original, and ornamental Design for a Pair of Eyeglasses, of which the following is a specification, reference being had to the accompanying drawing, forming part thereof.

Fig. 1 is a front perspective view of a pair of eyeglasses showing our new design.

Fig. 2 is a fragmentary enlarged vertical sectional view taken on the line 2—2 of Fig. 1.

We claim:

The ornamental design for a pair of eyeglasses, as shown.

PHILIP SILLS.

FRANK P. PATALANO.
